(57) **CLAIM**

The ornamental design for a lubrication gun housing, as shown and described.

DESCRIPTION

FIG. 1 is a perspective view of a lubrication gun housing showing our new design;

FIG. 2 is a top plan view thereof;

FIG. 3 is a right side elevational view thereof, the left side being a mirror image thereof;

FIG. 4 is a bottom plan view thereof;

FIG. 5 is an upside-down, head end view thereof; and,

FIG. 6 is a tail end view showing our new design.
